(57) **CLAIM**

The ornamental design for a golf club shaft, as shown and described.

DESCRIPTION

FIG. 1 is a top-left perspective view of an embodiment of a golf club shaft embodying our new design.

FIG. 2 is a right view of the golf club shaft with surface ornamentation shown in FIG. 1.

FIG. 3 is a left view of the golf club shaft shown in FIG. 1.

FIG. 4 is a top-left perspective view of the golf club shaft shown in FIG. 1; the grip and putter head shown in broken lines.

FIG. 5 is a front perspective view of the golf club shaft shown in FIG. 4.

FIG. 6 is a right view of the golf club shaft shown in FIG. 4; and,

FIG. 7 is a front view of the golf club shaft shown in FIG. 4.

The broken lines in the drawings depict environmental structures that form no part of the claimed design.

1 Claim, 7 Drawing Sheets
